CLAIM

The ornamental design for a side air vent for automobile and/or other replica, as shown and described.

DESCRIPTION

FIG. 1 is a right, front perspective view of a side air vent for automobile and/or other replica showing our new design; FIG. 2 is a rear, right isometric view thereof; FIG. 3 is a right, rear perspective view thereof; FIG. 4 is a left side elevation view thereof; FIG. 5 is a front elevation view thereof; FIG. 6 is a rear elevation view thereof; and, FIG. 7 is a top plan view thereof.

The dot-dash lines that depict boundary surrounding the claimed design and the broken line portions of the automobile shown throughout the drawing views are for illustrative and environmental purposes that form no part of the claimed design.

The evenly spaced broken lines in the drawings illustrate portions of the side air vent for automobile and/or other replica that form no part of the claimed design.
